(57) **CLAIM**

The ornamental design for a caster, as shown and described.

DESCRIPTION

FIG. 1 is a front perspective view of a caster, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view thereof, shown in an environment of use;

FIG. 10 is a front perspective view thereof, shown in alternate environment of use;

FIG. 11 is a front perspective view thereof, shown in another alternate environment of use;

FIG. 12 is a front perspective view thereof, shown in another alternate environment of use; and,

FIG. 13 is a front perspective view thereof, shown in another alternate environment of use.

The broken lines in the drawings illustrate the portions of the caster, which form no part of the claimed design.

1 Claim, 13 Drawing Sheets
